UNITED STATES PATENT OFFICE.

FREDERICK J. DECKER, OF ROCHESTER, NEW YORK, ASSIGNOR TO SHAFFER-DECKER CO., INC., OF ROCHESTER, NEW YORK, A CORPORATION.

PORTABLE GRINDING-MACHINE.

1,316,942.

Specification of Letters Patent. Patented Sept. 23, 1919.

Application filed March 13, 1918. Serial No. 222,097.

To all whom it may concern:

Be it known that I, FREDERICK J. DECKER, a citizen of the United States, residing at Rochester, in the county of Monroe and State of New York, have invented a new and Improved Portable Grinding-Machine, of which the following is a specification.

This invention while relating to grinding machines in general has more especial reference to those of the portable type and is particularly adaptable for use in grinding commutators of dynamo-electric machines.

One of the objects of my present invention is to provide a portable means for truing or resurfacing revolving cylindrical bodies such, for instance, as commutators without having to remove them from the machines of which they form a part as doing so, especially in removing the commutators of large dynamo-electric machines, involves considerable time, labor and expense.

It is necessary that commutators be resurfaced from time to time to preserve cylindricity because, in action, they are subject to uneven wear from friction of the brushes and the burning action of destructive sparks; and it is a further object of my invention to make use of a grinding wheel as the resurfacing means and to support the wheel in such manner that the operation may be performed while the commutator is revolving at normal or even greater than normal speed, thus assuring more perfect cylindricity.

Another object of the invention is to construct the machine with such features of adjustment that it can be placed in approximately operative position and then readily adjusted in a manner to bring the axis of rotation of the grinding wheel parallel with that of the commutator and at a proper height relatively thereto.

Another object of the invention is to provide a lateral feed for the grinding wheel of such a nature that an extremely fine adjustment can be made and a very fine cut taken off the surface of the commutator.

These and other objects of the invention pertaining more to details of construction will be more clearly brought out in the following description and particularly defined in the appended claims.

While I have referred to my invention as particularly adaptable for grinding commutators and will throughout the specification

speak of it as used for such purpose, it will, of course, be readily understood that a machine constructed in accordance therewith may as effectively be used for grinding other revolving cylindrical bodies so supported that the grinding wheel can engage and traverse their surface.

The accompanying drawings illustrating a machine constructed in accordance with my invention are as follows:—

Fig. 1 is a plan view of the machine with parts broken away to more clearly show details of construction.

Fig. 2 is a side elevation of the machine with parts broken away to more clearly show details of construction and with the motor removed.

Fig. 3 is a longitudinal sectional detail taken on the line 3—3 of Fig. 1.

Fig. 4 is a transverse sectional view of the base taken on the line 4—4 of Fig. 2.

Fig. 5 is a plan view of the right hand end portion of the base with respect to Fig. 2.

Fig. 6 is a vertical sectional view taken on the line 6—6 of Fig. 1.

Fig. 7 is a sectional view taken on the line 7—7 of Fig. 8.

Fig. 8 is a sectional view taken on the line 8—8 of Fig. 2.

Fig. 9 is a vertical sectional detail on the line 9—9 of Fig. 1 showing the manner of adjustably supporting the motor upon the bracket therefor.

Similar reference numerals refer to similar parts throughout the drawings.

The numeral 1 represents the base which is of rectangular conformation and comprises right and left hand transverse covered portions 2 and 3, respectively, connected by side walls 4 having reinforcing ribs 5 and inwardly extending flanges 6 along their lower edges.

Supported upon the base portion 3 and pivotally connected thereto by a centrally disposed vertically extending bolt 7 is a swivel head 8, such bolt being provided on its upper end with a nut 9 which, when loosened, permits an angular adjustment of the head. This head 8 is formed with a pair of oppositely positioned upright arms 10 having split bearings at their upper ends, provided with clamping bolts 11, and in which bearings are supported the ends of a bolt or shaft 12. Revoluble on the bolt 110

12 and engaging between the arms 10, 10 to prevent endwise movement is an extension member 13 formed integrally with a tube supporting head 14 having a bore at 5 right angles to that of the extension member. This extension member is slotted at 15 in the manner shown and provided with clamping bolts 16 whereby it is normally held against rotation. It will thus be seen 10 that the tube head 14 may be angularly adjusted about both a vertical and a longitudinal axis.

Movably supported upon the right hand transverse base portion 2 is a standard 17 having arms 18 extending upward from its ends, such arms having slots 19 therethrough each forming an arc of a circle having a radius extending from the axial center of the bolt 12 and these arms are recessed on 20 their outer faces to receive the heads 20 and nuts 21 of tie-bolts 22 engaging through laterally extending bosses 23 formed on the right hand tube supporting head 24.

Supported in the heads 14 and 24 and extending slightly beyond the outer ends thereof is a tube 25 which is held against longitudinal movement by right and left hand cap members 26 and 27, respectively, secured to the tube by screws 28 and having 30 their inner ends engaging the outer ends of their respective head members. The head 24 is slotted along the top and the head 14 along one side, in the manner shown, and the tube 25 is normally held against rotation by the upper tie-bolt 22 for the head 24 and a clamping bolt 29 for the head 14 which engages through the upper and is threaded in the lower one of bosses 30 formed thereon. The tie-bolts 22 are keyed 40 to the tube head 24 at 31 to prevent their rotation. Loosening the nuts 21 on the tie-bolts 22 and the clamping bolts 16 hereinbefore described permits an angular raising or lowering in a vertical plane of the tube 25 45 which is affected in the following manner:

The tube head 24 rests upon the head 32 of a vertically extending bolt 33 threaded in the upper end of a tubular member 34, such member extending through a projection 35 in the center of the base portion of the standard 17 and being held in its proper position of vertical adjustment by a nut 36 threaded thereon. The bolt 33 is raised or lowered by turning with a suitable wrench and as it is raised it carries with it the head 24 and tube 25 and as it is lowered these members drop by gravity.

The tubular member 34 engages through a curved slot 37 formed in the top wall of 60 the base portion 2 and has a head 38 on its lower end having side walls straddling a lateral adjusting screw 39 which are slotted to receive the trunnions 40 of a trunnion nut 41 movable on such screw. This lateral adjusting screw 39 is revolvably supported in

the side walls of the right hand base portion 2 and is held against endwise movement by its head 42 and nut 43. It will thus be seen that by turning the screw 39 the trunnion nut may be moved either to the right or left 70 as desired and that such nut by its engagement with the head 38 of the tubular member 34 will affect a lateral movement of the standard 17 and the consequent angular adjustment of the tube 25 in a horizontal 75 plane with the bolt 7 as the axis of rotation.

The cap members 26 and 27 are formed with inwardly extending central portions forming bearings for a feed screw 44 within the tube 25 and which is held against end 80 play by a nut 45 on the left and the hub of a hand wheel 46 keyed to the right hand ends thereof, such nut 45 and hand wheel 46 having suitable washers disposed between them and their respective cap members. 85

Threaded on the said feed screw 44 is a nut 47 having a spline 48 engaging in a channel 49 formed in the top of the tube 25 and extending between the inner ends of the tube heads 14 and 24. This spline engages 90 in a recess formed in an offset portion 50 of a sleeve 51 slidable on the supporting tube 25 and is secured to such sleeve by screws 52; while to permit the sleeve to move freely on the supporting tube the sleeve is slotted longitudinally along one side, in the manner shown, and provided with lugs 53 for receiving the clamping bolts 54 which are adjusted to secure a proper fitting of the parts. Formed integrally with the sleeve 51 is a 100 motor supporting bracket 55 extending outwardly therefrom, or toward the observer with respect to Fig. 1, and reinforced by webs 56.

Supported upon this bracket 55 is a motor 57 the feet 58 of which rest upon the finished surfaces of the raised corners 59, and the motor is held in proper position of adjustment back or forth on the bracket, for the purpose hereinafter described, by the 110 studs 60 provided with clamping nuts 61 and 62 and spring washers 63 engaging between the nuts 62 and the under side of the bracket. The bottoms of the feet 58 are grooved to receive longitudinally extending 115 and parallel guiding bars 64 slidable with the motor when the same is being adjusted and engaging in channels 65 therefor in the raised corners 59 of the bracket and these raised corners are also slotted at 66 to receive and permit movement of the motor studs. To the front of the motor there is bolted a plate 67 comprising a nut into which is threaded one end of a short feed screw 68 the other end of which is revolvably supported in a centrally disposed extension 69 formed on the bracket 55, and on this feed screw between the bracket extension 69 and a retaining nut 70 is an operating crank 71 provided with a handle 72. Turning this 120

crank will effect an adjustment back or forth as desired of the motor on its support for the purpose of tightening the belt 73, as will be explained. While the nuts 61 and 62 on the motor studs 60 will be turned sufficiently tight to hold the motor against any accidental movement back or forth due to vibration during the operation of the machine, the motor is not clamped to the bracket, due to the action of the spring washers 63, so rigidly but what it can be adjusted by means of its feed screw 68 without the necessity of adjusting the nuts on the studs each time such motor adjustment is required.

Also formed integrally with the sleeve 51 and extending parallel therewith but on the side opposite the motor bracket 55 is a tubular arm 74 connected to the sleeve by a pair of outwardly extending vertical ribs or arms 75 and a centrally disposed longitudinal extending web 76. The ends of this tube 74 comprise bearings for a spindle tube 77 mounted therein and secured within this spindle tube at its right and left hand ends by screws 78, with reference to Fig. 1, are eccentrics 79 and 80, respectively, while threaded within these eccentrics are tapered thrust bushings 81 forming bearings for a spindle shaft 82. The tubular arm 74 is slotted at each end but on reverse sides and for a distance approximately the length of the eccentrics 79 and 80 and is provided above and below such slots with lugs 83 for receiving clamping bolts 84, these bolts being adjusted to permit rotation of the spindle tube 77 but not too freely.

The right hand end of the tube 77 extends slightly beyond its supporting arm 74 and has fixed thereon a worm wheel 85 which meshes with a worm 86 fixed to a shaft revolvably supported in bearings formed on a bracket 87 secured to the right hand connecting arm 75 and having fixed thereto above such bracket the shank 88 of a suitable operating handle 89. Threaded on the right hand end of the shaft 82 are a pair of thrust bearing adjusting nuts 90 between which and their respective thrust bearing 81 are a pair of metal collars 91 with a fiber collar 92 between them; and keyed to the outer end of the shaft is a pulley 93 alined with a pulley 94 fixed to the motor shaft 95. Keyed to the reduced portion of the shaft 82 at its opposite end is a coupling flange 96 between which and the head of its respective thrust bearing 81 is a fiber collar 97 and a steel collar 98, while fixed to the shaft at the end of this coupling flange is the hub 99 on which is secured the grinding wheel 100. Nuts 101 threaded on the ends of the shaft hold the wheel 100 and pulley 93 in place. The grinding wheel may be of any preferred type according to the work to be done but when the machine is used for grinding com-

mutators a wheel especially made for this purpose is used.

As the nut 47 is moved in one direction or the other on the feed screw 44 by turning the hand wheel 46 it carries with it the sleeve 70 51 and parts supported thereby, viz.,—the motor bracket 55 and tubular arm 74 with their respective members. In this manner the grinding wheel is caused to traverse the face of the commutator, or other object being ground, and to limit the distance of such travel, split stop rings 102 encircle the supporting tube 25, one each side of the sleeve 51, and are adapted to be clamped to the tube in any desired position of longitudinal adjustment by the bolts 103 carried thereby.

From the description it will be noticed that the wheel shaft 82 is eccentrically supported and that by rotating the eccentrics 85 79 and 80 through the medium of the tube 82, worm wheel 85, worm 86 and operating handle 89, a lateral movement of the grinding wheel 100 in one direction or the other is effected. This lateral feed of the grinding 90 wheel, it will of course be understood, is to bring the wheel into contact with the surface of the object to be ground and the eccentric movement permits of an extremely fine feed adjustment. The shaft 82 is 95 driven from the motor shaft 95 by means of the belt 73 engaging over their respective pulleys 93 and 94, and this belt is tightened by the adjustment back or forth of the motor 57, in the manner hereinbefore described, 100 such adjustment being necessitated by the lateral movement of the shaft 82. The grinding wheel travels in the reverse direction to that of the object being ground.

The spline 48 prevents rotation of the 105 sleeve 51 on the supporting tube 25, but should it be desired in the adjustment of the machine to raise or lower the axis of rotation of the grinding wheel relatively to that of the object being ground the same may be 110 accomplished by loosening the clamping bolts of the tube heads 14 and 24 and giving the supporting tube 25 the required amount of rotation which can be done by the operator lifting or lowering, as required, either the motor bracket 55 or the tubular arm 74. When this adjustment has been made the aforesaid clamping bolts are again tightened.

When the machine is used for grinding 120 commutators it is set up in the following manner:—

It should first be understood that only enough of the frame work supporting the commutator and the commutator brushes 125 themselves need be removed that will permit the grinding wheel being brought into engagement with the periphery of the commutator across its entire surface. The machine is secured to a heavy plank indicated 130

at 104 in Figs. 2 and 4, by means of base clamping plates 105 which extend between the side walls 4 of the base and engage the flanges 6, each of such plates having a central vertical projection 106 bored out to receive a bolt 107 which also extends through a hole in the plank and has a clamping nut, not shown, threaded on its lower end. The plank 104 is then supported upon blocks 10 so that the machine will be approximately in the desired position, after which the several adjustments of the machine are made as follows:—

First, true horizontal position for the supporting tube 25 is secured by raising or lowering the same by turning the vertical adjusting bolt 33 in the manner described and after which the nuts 21 on the bolts 22 of the supporting head 24 and the bolts 16 of the head 14 are tightened; and, to be able to readily determine when the supporting tube is level, a spirit level 108 is provided on the sleeve 51 or in any other suitable position. The tubular arm 74, it will be understood, is always parallel with the supporting tube 25 so that when one is in horizontal position the other is also. Then, if a lateral adjustment is necessary in order to bring the face of the grinding wheel 100 parallel with that of the commutator, indicated at 109 in Fig. 1, the screw 39 is operated which effects an angular rotation of the supporting tube 25 and parts carried thereby on the bolt 7 as an axis, and when this adjustment has been made the nut on the pivot bolt is tightened to prevent further lateral movement. Should it be desired to adjust the relative position, higher or lower, of the grinding wheel and commutator this may be accomplished by raising or lowering the tubular arm 74 which caused a partial rotation of the supporting tube 25 in the heads 14 and 24, after which the clamping bolts for such heads are tightened to secure this adjustment.

When operating the machine, the hand wheel 46 is turned to feed the grinding wheel back and forth across the commutator, and the handle 89 is turned to feed the grinding wheel into engagement with and away from the commutator. As hereinbefore stated, the grinding wheel revolves in a reverse direction to that of the commutator and the grinding is done while the latter is traveling at its normal or even greater than normal speed. I have found it necessary, also, when grinding commutators, that the cut be regulated according to the current of the motor for driving the grinding wheel, and for this reason an ammeter connected in series with the motor is placed in such position that it can at all times be read by the operator of the machine.

The machine may be used for grinding, burnishing or other like purposes and the

kind of wheel 100 that is used will be determined accordingly, one of special composition for grinding copper being employed when the machine is used on commutators; but as the machine is primarily a grinder I will refer to the element 100, in the claims, as a grinding wheel although not necessarily limiting the invention to the use of such.

It is believed that from the foregoing description the purpose, construction and manner of operating the grinding machine are sufficiently clear to call for no further explanation herein.

What I claim is:—

1. In a machine of the character described, a support, a member slideable on said support, bearings and a motor bracket both carried by said slideable member, a shaft revolvably supported in said bearings, a grinding wheel fixed to said shaft, a motor supported on said bracket, and connections between said motor and said shaft for driving the shaft. 80

2. In a machine of the character described, a support, a member slideable on said support, bearings and a motor bracket carried by said slideable member on opposite sides of said support, a shaft revolvably supported in said bearings, a grinding wheel fixed to said shaft, a motor supported on said bracket, and connections between said motor and said shaft for driving the shaft. 90

3. In a machine of the character described, a support, a member slideable on said support, bearings and a motor bracket carried by said slideable member on opposite sides of said support, a laterally adjustable shaft revolvably supported in said bearings, a grinding wheel fixed to said shaft, a motor adjustably supported on said bracket, and connections between said motor and said shaft for driving the shaft. 100

4. In a machine of the character described, a support pivotally mounted to be swung in both a vertical and a horizontal plane, a member longitudinally slideable on said support and having an angular adjustment in a plane at right angles to such longitudinal movement, an adjustably supported motor and bearings both carried by said slideable member, a laterally adjustable shaft revolvably supported in said bearings, a grinding wheel fixed to said shaft, and connections between said motor and said shaft for driving the shaft. 110

5. In a machine of the character described, a supporting tube, a sleeve slideable on said tube, a tubular arm and a motor bracket carried by the sleeve on opposite sides of said tube, a shaft revolvably supported in said arms, a grinding wheel fixed to said shaft, a motor supported on the said bracket, and connections between said shaft and said motor for driving the shaft. 125

6. In a machine of the character described,

- a supporting tube, a sleeve slidable on said tube, a tubular arm and a motor bracket carried by the sleeve on opposite sides of said tube, a shaft revolubly supported in said tube, means for laterally moving said shaft, a grinding wheel fixed to said shaft, a motor adjustably supported on the said bracket, and connections between said shaft and said motor for driving the shaft.
- 10 7. In a machine of the character described, a supporting tube, a sleeve slidable on said tube, a tubular arm and a motor bracket carried by the sleeve on opposite sides of said tube, eccentrics revoluble in said arm, a shaft revolubly supported in said eccentrics, means connecting said eccentrics to cause like rotation thereof, means for rotating said eccentrics to effect a lateral movement of the shaft, a grinding wheel fixed to one end of said shaft, a motor adjustably supported upon said bracket, and connections between the opposite end of said shaft and said motor for driving the shaft.
- 15 8. In a machine of the character described, a base, a swivel head supported on the base and having a vertical axis of rotation, arms on said head, a horizontally disposed shaft supported in said arms and means for normally securing the same against rotation,
- 20 30 a member rotatably mounted on said shaft, a supporting head formed on said member and having a bore at right angles to said shaft, a tube supported by and rotatable in said head, and means as clamping bolts, for normally holding the said rotatable members in their respective positions of angular adjustment.
- 25 9. In a machine of the character described, a base, a tubular member pivotally supported at one end above said base so that its position may be adjusted angularly in a vertical plane, a standard supported on said base, and a supporting head for the other end of said tubular member slidably supported in said standard.
- 30 40 10. In a machine of the character described, a base, a tubular member pivotally supported at one end above said base so that its position may be adjusted angularly in both a vertical and a horizontal plane, a standard laterally adjustable on said base, and a supporting head for the other end of said tubular member slidably supported in said standard.
- 45 50 55 60 65 11. In a machine of the character described, a base, a tubular member pivotally supported at one end above said base so that its position may be adjusted angularly in both a vertical and a horizontal plane, a standard laterally adjustable on said base, such standard comprising a base portion and a pair of upwardly extending slotted arms, a supporting head for the opposite end of said tubular member engaging between the said arms, and means, as bolts extending
- through the supporting head for adjustably securing the same to said arms.
12. In a machine of the character described, a base, a standard supported on the base, a member vertically slidable in said standard, a vertical adjusting screw threaded into said standard and having one end engaging the said member, and means for securing the said member to the standard.
13. In a machine of the character described, a base having a guiding slot therein, a lateral feed screw supported in said base, a standard laterally adjustable on said base, a trunnion nut on said feed screw, a head straddling said feed screw and slotted to receive the trunnions on said nut, and an extension from said head engaging through the said slot and secured to said standard, all for the purpose set forth.
14. In a machine of the character described, a base having a guiding slot therein, a lateral feed screw supported in said base, a standard laterally adjustable on said base, a trunnion nut on said feed screw, a head straddling said feed screw and slotted to receive the trunnions on said nut, a tubular extension on said head engaging through the said slot and secured to said standard, and a vertical adjusting screw threaded into said tubular extension, all for the purpose set forth.
15. The combination, in a machine of the character described, of a base, a supporting tube having a longitudinally extending slot, members on said base for supporting the said tube, a longitudinal feed screw supported within said tube and means for operating the same, a sleeve slidable on said tube, a tubular arm and a motor bracket formed on said sleeve on opposite sides of the tube, a spline engaging in the said slot and secured to said sleeve, a nut on said feed screw formed integrally with said spline, a shaft revolubly supported in said tubular arm, means for laterally adjusting the shaft, a motor adjustably supported on said bracket, a grinding wheel fixed to one end of said shaft, and connections between the other end of said shaft and said motor for driving the shaft.
16. The combination, in a machine of the character described, of a base, a supporting tube having a longitudinally extending slot, members on said base for supporting the said tube, a longitudinal feed screw supported within said tube and means for operating the same, a sleeve slidable on said tube, a tubular arm and a motor bracket formed on said sleeve on opposite sides of the tube, a spline engaging in the said slot and secured to said sleeve, a nut on said feed screw formed integrally with said spline, a shaft revolubly supported in said tubular arm, means for laterally adjusting the shaft, a motor adjustably supported on said

bracket, a grinding wheel fixed to one end of said shaft, connections between the other end of said shaft and said motor for driving the shaft, and stop rings adjustable on said supporting tube for limiting the movement of said sleeve.

17. The combination, in a machine of the character described, of a base, a supporting tube having a longitudinally extending slot, members on said base for supporting the said tube, a longitudinal feed screw supported within said tube and means for operating the same, a sleeve slidable on said tube, a tubular arm and a motor bracket formed on said sleeve on opposite sides of the tube, a spline engaging in the said slot and secured to said sleeve, a nut on said feed screw formed integrally with said spline, a tube revolvably supported in said tubular arm, eccentrics secured within said second named tube, a shaft revolvably supported in said eccentrics, a worm wheel on the said second named tube, a worm in mesh with said wheel, bearings on said tubular arm for said worm, means for operating the said worm to effect through the rotation of said eccentrics a lateral adjustment of said shaft, a motor adjustably supported on said bracket, a grinding wheel fixed to one end of said shaft, and connections between the other end of said shaft and said motor for driving the shaft.

18. The combination, in a machine of the character described, of a base, a supporting tube having a longitudinally extending slot, such tube being supported above said base in a manner that its position may be adjusted angularly in a vertical plane and means for effecting said adjustment; members on said base for rotatably supporting said tube and means for normally securing it against rotation; a longitudinal feed screw supported within said tube and means for operating the same, a sleeve slidable on said tube, a tubular arm and a motor bracket formed on said sleeve on opposite sides of the tube, a spline engaging in the said slot and secured to said sleeve, a nut on said feed screw formed integrally with said spline, a shaft revolvably supported in said tubular arm, means for laterally adjusting the shaft, a motor adjustably supported on said bracket, a grinding wheel fixed to one end of said shaft, and connections between the other end of said shaft and said motor for driving the shaft.

19. The combination, in a machine of the character described, of a base, a supporting tube having a longitudinally extending slot, such tube being supported above said base in a manner that its position may be adjusted angularly in a horizontal plane and means for effecting said adjustment; members on said base for rotatably supporting said tube and means for normally securing it

against rotation; a longitudinal feed screw supported within said tube and means for operating the same, a sleeve slidable on said tube, a tubular arm and a motor bracket, formed on said sleeve on opposite sides of the tube, a spline engaging in the said slot and secured to said sleeve, a nut on said feed screw formed integrally with said spline, a shaft revolvably supported in said tubular arm, means for laterally adjusting the shaft, a motor adjustably supported on said bracket, a grinding wheel fixed to one end of said shaft, and connections between the other end of said shaft and said motor for driving the shaft.

20. The combination, in a machine of the character described, of a base, a supporting tube having a longitudinally extending slot, such tube being supported above said base in a manner that its position may be adjusted angularly in both a vertical and a horizontal plane and means for effecting each of said adjustments; members on said base for rotatably supporting said tube and means for normally securing it against rotation; a longitudinal feed screw supported within said tube and means for operating the same, a sleeve slidable on said tube, a tubular arm and a motor bracket formed on said sleeve on opposite sides of the tube, a spline engaging in the said slot and secured to said sleeve, a nut on said feed screw formed integrally with said spline, a shaft revolvably supported in said tubular arm, means for laterally adjusting the shaft, a motor adjustably supported on said bracket, a grinding wheel fixed to one end of said shaft, and connections between the other end of said shaft and said motor for driving the shaft.

21. The combination, in a machine for grinding commutators, of a base, a supporting tube having a longitudinally extending slot, members on said base for supporting the said tube, a longitudinal feed screw supported within said tube and means for operating the same, a sleeve slidable on said tube, a tubular arm and a motor bracket formed on said sleeve on opposite sides of the tube, a spline engaging in the said slot and secured to said sleeve, a nut on said feed screw formed integrally with said spline, a shaft revolvably supported in said tubular arm, means for laterally adjusting the shaft, a motor adjustably supported on said bracket, a grinding wheel fixed to one end of said shaft, and connections between the other end of said shaft and said motor for driving the shaft, the said grinding wheel being adapted to travel in a reverse direction from that of the commutator and to permit the latter to revolve at a normal or greater than normal speed.

22. A grinding machine comprising a base, a guide, a connection between the base and the guide permitting the latter to swing

about two axes at right angles to each other and to the guide, a carriage movable on the guide, a member mounted to turn on the carriage about an axis parallel with the 5 guide, and a grinder eccentrically carried by said member so that the turning of the member effects the feeding of the grinder.

23. A grinding machine comprising a base, a guide, a carriage movable along the 10 guide, a member mounted to turn on said carriage about the axis parallel with the guide, and a grinder eccentrically carried by said member so that the turning of the member effects the feeding of the grinder.

15 24. A grinding machine comprising a base, a guide, a connection between the base and the guide permitting the guide to turn about two axes at right angles to each other and to the guide, a carriage movable along the 20 guide, a tubular member rotatable on the carriage about an axis parallel with the guide, a shaft extending through the tu-

bular member and arranged eccentrically with reference to said member, and a grinder carried by said shaft. 25

25. A grinding machine comprising a base member, a guide, a connection between the guide and the base member permitting the guide to swing about two axes at right angles to each other and to the guide, a 30 carriage adapted to move on the guide, a member mounted to rotate on the carriage about an axis parallel with the guide, a grinder carried by said rotary member mounted to turn about an axis eccentrically 35 to and parallel with said rotary member so that the turning of the rotary member effects the feeding of the grinder, a mechanism for turning said rotary member comprising a worm wheel on the rotary mem- 40 ber, and a worm coöperating with said worm wheel and acting to lock the rotary member in its adjusted position.

FREDERICK J. DECKER.
